SPECIFICATION forming part of Design No. 19,813, dated May 6, 1890.

Application filed April 11, 1890. Serial No. 347,538. Term of patent 3½ years.

To all whom it may concern:

Be it known that I, JAMES L. FOLSOM, a citizen of the United States, and a resident of the city of Brooklyn, in the county of Kings and State of New York, have invented a new and original Design for Carpets, of which the following is a specification, reference being had to the accompanying photograph, which forms a part of the same.

10 The invention relates to a design to be worked into or upon surfaces, such as carpets or similar fabrics; and it consists in the novel configuration and grouping of figures herein specifically shown and claimed.

The accompanying photograph is a facee 15 view of a carpet showing my new design.

My design consists of irregular blocks or panels filled with scroll forms, the dividing lines between the panels being formed by larger scroll forms. 20

What I claim as new, and desire to secure by Letters Patent, is—

The design for carpets, consisting of the design substantially as shown.

JAS. L. FOLSOM.
